UNITED STATES PATENT OFFICE

ARTHUR E. PAIGE, OF PHILADELPHIA, PENNSYLVANIA, ASSIGNOR TO JOHN WOOD MANUFACTURING COMPANY, OF CONSHOHOCKEN, PENNSYLVANIA, A CORPORATION OF PENNSYLVANIA

HEAT EXCHANGE APPARATUS

Original application filed January 18, 1928, Serial No. 247,696. Divided and this application filed December 10, 1929. Serial No. 412,972.

This is a division of my original application Serial No. 247,696 filed January 18, 1928, for Letters Patent of the United States for improvement in methods of heating and ventilating.

My invention relates to heating systems including a furnace comprising a fuel burner in cooperative relation with a container in which any suitable heating fluid, for instance, steam or water, may be heated; and conduits forming a circulatory system leading from and returning to said container and supplying said heating fluid to a radiator or radiators, to heat the atmosphere local to the radiator surface. The purpose and effect of my invention are to facilitate and augment the transfer of heat from the radiator surface to the adjacent atmosphere by more rapid displacement of the air at such surface than is possible by convection; and at a rate variable with the heat supplied.

As hereinafter described, my invention includes a means for facilitating and augmenting the transfer of heat from a fluid supplied to a radiator to the atmosphere adjacent to the radiator, by utilizing power from the heating fluid to operate a motor to forcibly circulate the air relatively to the radiator, by means of a rotary fan.

The typical heating system herein disclosed includes a gas burning water heater and means for maintaining a forced circulation of water within the heating system, by an electrically controlled pump; the operation of the device being controlled by thermostatically operative means; and the forced circulation of air through the radiator is effected by a motor included in a bypass short-circuiting the radiator with which it is associated; so that the heating fluid is taken into the motor from the supply conduit leading from the heater to the radiator, and the exhaust from the motor is discharged into the return pipe leading from the radiator back to the heater.

My invention includes the various novel features of construction, arrangement and procedure hereinafter more definitely specified.

In said drawings; Fig. I is a diagram show-

ing a house heating system embodying my invention.

Fig. II is a vertical sectional view of one of the radiator structures shown in Fig. I, taken on the line II, II.

Fig. III is a plan sectional view of said structure, taken on the line III, III in Figs. I and II.

Fig. IV is a fragmentary sectional view of the fluid motor indicated in Figs. I and II.

Fig. V is a fragmentary sectional view of a modified form of fluid motor.

Referring to Fig. I; the house or other building, comprising rooms or other inclosures 2 and 3, has, preferably in the cellar 4 thereof, the heater 6 inclosing the burners 7 and 8 supplied with gas from the conduit 9 under control of the thermostatically operative valve in the casing 10. Said valve casing carries the tubular thermostatic element 70 11 extending within the water conduit 12 which is connected with the pipe 14 through which hot water is delivered from the cellular heater units 16 which are supplied with cold water through the pipe 18. Said conduit 12 is connected by pipes 20 with radiator units 21, from which the water is returned through pipes 23 to the pump 24 which is connected to said pipe 18 and arranged to be operated by the electric motor 25, under control of the thermostatically operative switches 27, which are respectively local to the radiators 21 as indicated in Fig. I. Said pump is operated to circulate the water through the system in the direction indicated by the arrows.

Referring to Figs. II, III and IV; each of said radiators 21 comprises a cellular structure 30 which is a rectangular congeries of metal tubes 31 having enlarged polygonal 90 ends 32 which fit together and are sealed in connection with a casing band 33 so as to form a cellular honeycomb of thin metal walls and comprising separate passageways 35 for hot water or steam and 36 for atmospheric air. Said radiator includes the inlet port 38 and the outlet port 39 in communication with said passageways 35 for the heating medium. The outer casing 40 for said congeries 31 forms a cold air inlet chamber 100

41 at the bottom thereof, an intermediate chamber 42 containing said cellular structure, and an upper outlet chamber 43 for the heated air. The fluid motor 45 is preferably mounted in said inlet chamber 41 with a fan 46 arranged to draw air into said outer casing 40 through the stationary louvers 47 in the lower portion of said casing and force it through the passageways 36 in said congeries of tubes, and out from the heated air chamber 43 into the surrounding atmosphere, through the foraminous panel or grille 49.

Said fluid motor 45 includes an outer casing 50 provided with ports 51 and 52 through which the heating fluid in the system circulates from the pipes 20 to the pipes 23. Said casing 50 contains the rotor 54, the blade 55, and the shaft 56 which latter is journaled in said casing and in operative connection with said fan 46. Valves 57 and 58 may be provided local to said motor casing to variably determine, by manual adjustment thereof, the relative volume of the heating fluid which shall be directed to the radiator 21 and through the motor 45. It is to be understood that said valves may be adjusted to vary and determine the speed of rotation of the motor and consequent air displacement effect of said fan 46 to attain the desired efficiency of transfer of heat from the radiator to the surrounding atmosphere; it being noted that such capacity should be increased and diminished in accordance with increase and decrease in the heat supplied to the radiator. Although said fan 46 is indicated as in coaxial relation with said shaft 56, it is to be understood that it may be connected therewith by gearing, so as to be turned at a faster rate than said shaft.

Although I find it convenient to employ a fluid motor of the rotary type indicated in Fig. IV; any other suitable type of motor may be employed. For instance, Fig. V shows a fluid motor 59 of the reciprocatory type. The fan 46 may be mounted directly upon the shaft 60 or, as shown, the fly wheel 61 may be connected by a belt 62 with a pulley 63 on the shaft 65 which carries a fan 46. Said motor 59 may be included in multiple relation with a radiator 21 in a bypass from the supply pipe 20 to the exhaust return pipe 23 and be controlled by valves 57 and 58 as above described; but the fluid may be otherwise exhausted from said motor.

Therefore, I do not desire to limit myself to the precise details of construction, arrangement, or procedure herein set forth, as it is obvious that various modifications may be made therein, without departing from the essential features of my invention, as defined in the appended claims.

I claim:

1. The combination with a radiator structure forming separate passageways for a heating fluid and air; of conduits for heating fluid

leading to and from said radiator structure; means arranged to forcibly circulate air through the air passageways, including a rotary fan and a motor operatively connected with said fan; means arranged to operate said motor by power from the heating fluid, including conduits leading to and from said fan motor and in multiple relation with said radiator conduits; and valve controlling means, respectively in said radiator and motor conduits arranged to variably determine the relative volumes of heating fluid respectively supplied to said radiator and fan motor; whereby all of the heating fluid utilized in operating said fan motor is returned into the radiator system to be reheated.

2. In heat exchange apparatus; the combination with a casing, having an air inlet near the bottom thereof and an air outlet near the top thereof, of a cellular structure, in said casing, between said inlet and outlet, forming separate passageways for a heating fluid and air; conduits for heating fluid leading to and from said cellular structure; means arranged to forcibly circulate air through said air passageways, including a rotary fan and a motor for the same in said casing between said air inlet and said cellular structure; means arranged to operate said motor by power from the heating fluid, including conduits leading to and from said motor and in multiple relation with said radiator conduits; means arranged to jointly supply said heating fluid to said cellular structure and to said motor; and valve controlling means, respectively in said conduits connected with said cellular structure and with said motor, arranged to variably determine the relative volumes of heating fluid respectively supplied to said cellular structure and to said motor; whereby the heat available in said cellular structure, and the speed of circulation of air with respect to said cellular structure, are adjustably variable.

In testimony whereof, I have hereunto signed my name at Philadelphia, Pennsylvania, this twenty-sixth day of November, 1929.

ARTHUR E. PAIGE.
